[57] **CLAIM**

The ornamental design for a novelty tennis racket having bent handle, as shown and described.

DESCRIPTION

FIG. 1 is a front perspective view of a novelty tennis racket having bent handle employing my new design; FIG. 2 is a right side elevation view of the tennis racket of FIG. 1;

FIG. 3 is a top plan view of the tennis racket of FIG. 1; and

FIG. 4 is a bottom plan view of the tennis racket of FIG. 1.

The back view of the tennis racket is substantially the same as FIG. 1 and the left side view is substantially the same as FIG. 2 except the handle is bent to the right.
